(57) **CLAIM**

The ornamental design for a racecar docking station for media player, as shown and described.

DESCRIPTION

FIG. 1 is a perspective view of a racecar docking station for a media player of the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof with a media player shown in dotted lines.

The broken lines represent the portions of the design that form no part of the claim.
